UNITED STATES PATENT OFFICE.

ARMAND MONARD, OF NEW YORK, N. Y.

FLEXIBLE SHAFT.

1,200,216.

Specification of Letters Patent.

Patented Oct. 3, 1916.

Application filed December 24, 1915. Serial No. 68,522.

To all whom it may concern:

Be it known that I, ARMAND MONARD, a citizen of Switzerland, and a resident of the city of New York, borough of Queens, Ridgewood, in the county of Queens and State of New York, have invented a new and Improved Flexible Shaft, of which the following is a full, clear, and exact description.

My invention relates to flexible shafts consisting of a plurality of interconnecting links, and the object thereof is to provide a simple and efficient shaft of comparatively little weight and great flexibility and in which the connections between the links are in the shape of spherical joints.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is an elevation of a section of a shaft embodying my invention; Fig. 2 is a plan view of a blank before the blank is drawn into a tubular section; Fig. 3 is a section through the blank drawn into a link; Fig. 4 is a section through a shaft fragment showing two links in connection and a third one ready to receive a succeeding link; Fig. 5 is a section on line 5-5, Fig. 4; Fig. 6 is a plan view of a blank having a modified locking arrangement for the locking of the link extensions; Fig. 7 is a section through the blank after being drawn into a link; Fig. 8 is a longitudinal section through a shaft portion formed of links, as shown in Figs. 6 and 7; Fig. 9 is a cross section through a link on line 9-9, Fig. 8; Fig. 10 is a plan view of a further modified blank; Fig. 11 is a section through a blank after the same is drawn; Fig. 12 is a section through a shaft section formed of such links; Fig. 13 is a section through a shaft section in which the tubular links are provided with reinforcing fillers; Fig. 14 is a cross section of such a shaft; and Fig. 15 is an elevation of a filler.

Referring particularly to Figs. 1 to 5 inclusive, 16 is a blank substantially circular in form having two diametrically opposite extensions 17. The blank has also a pair of

arcuate, diametrically opposite slots 18 disposed on an axis at right angles to the extensions. The edge of the blank has diametrically opposite, pointed portions 19 alining with the slots.

When the blank is turned into a link 20 the central part 21 of the blank is raised to form a semi-spherical partition 22 at one end of the tubular link resulted from the drawing of the blank. The openings 18 of the blank extend partly on the lateral surface of the link at the edge where the partition is formed and partly into the partition, as best seen in Fig. 4. These openings are adapted to receive the extensions 17 of another link. After the extensions have passed through the opening 18 they are bent to encompass the partition. It will be noted that one of the extensions 17 has a notch 23, while the other has a projection 24 adapted to fit into the notch 23 of the other extension, whereby the two ends are locked when the extension, with the projection, is folded over the extension with the recess. It is self-evident that the length of the extension 17 is just sufficient to encompass the partition when the ends are locked.

The pointed edges 19 of the blank form apexes disposed symmetrically with respect to the extensions 17 to which the edge of the tubular section slopes from each apex. The apexes of each link engage the edge of the adjacent link and prevents any relative axial displacement between adjacent links. The center of the semi-spherical partition 22 is in the plane of the edge formed by the partition with the body of the link; and since the apexes 19 are in contact with said edge they also lie in the plane in which the center of the semi-spherical partition lies. The said apexes form fulcrums or bearings in addition to the bearings formed by the engagement of the extensions with the partitions, as seen in Fig. 4. The displacement between two links is limited by the degree of sloping from the apexes to the extensions.

The blank 16' (see Figs. 6 to 9 inclusive) differs from the blank 16 only in the means for interlocking the extensions 17'. It will be noted that each extension has a pointed tooth 25, said teeth being on opposite sides of said extensions so that when the extensions are made to encompass the semi-spherical partition 22' the ends will splice by the engagement of the teeth, as shown in Fig. 9. The engagement or the splicing of the ex-

tension ends interlocks the ends, and considerable stress may be applied longitudinally on the shaft without in any way endangering the parting of the interconnecting links. In cases where the blank is of considerable thickness (see Figs. 10 to 12 inclusive), the extensions 17" have no interlocking means, for the strength of the extension is sufficient to overcome any longitudinal stress upon the shaft. The said extensions 17" may be long enough to meet, but this is not necessary, for if they only partially encompass the semi-spherical partition 22" they will answer the purpose, as can be easily seen from the drawings.

In Figs. 13 to 15 inclusive the links 20' are provided with fillers to increase the lateral strength of the shaft, for each link will be reinforced by a filler 26 which extends from the encompassing extensions 17' to the semi-spherical partition 22' of the adjacent link. It will be noted from Fig. 13 that the fillers are placed into position as the shaft is built up by the connection of the links. Preferably one end of the filler 26 is concave, having a curvature substantially that of the encompassing end 17'. The other end of the filler is convex, having a curvature substantially that of the semi-spherical partition 22'. It will be noted that the flexible shaft in which the links are reinforced by fillers will not only increase the lateral strength of the shaft but also its longitudinal resistance.

35 While I have described the principle of operation together with the device which I now consider to be the best embodiment thereof, I desire to have it understood that the device shown is merely illustrative and 40 that such changes may be made as are within the scope of the appended claims.

I claim:

1. A flexible shaft consisting of tubular links each having an inwardly raised, semi-spherical partition at one end thereof and an extension at the other end adapted to engage an adjacent link and encompass the semi-spherical partition of the said adjacent link.

50 2. A flexible shaft consisting of tubular links each having an inwardly raised, semi-spherical partition at one end thereof, each link having diametrically opposite slots at the edge of said partition, and diametrically opposite extensions from the other end of said link in a plane at right angles to the plane of the slots, said extensions engaging the slots of an adjacent link and encompassing the semi-spherical partition thereof.

60 3. A flexible shaft consisting of tubular links each having an inwardly raised, semi-spherical partition at one end thereof, each link having diametrically opposite slots at the edge of said partition, diametrically opposite extensions from the other end of said

link in a plane at right angles to the plane of the slots, said extensions engaging the slots of an adjacent link and encompassing the semi-spherical partition thereof, the extensions encompassing the partition having means locking the ends thereof.

4. A flexible shaft consisting of tubular links each having an inwardly raised, semi-spherical partition at one end thereof, each link having diametrically opposite slots at the edge of said partition, and diametrically opposite extensions from the other end of said link in a plane at right angles to the plane of the slots, said extensions engaging the slots of an adjacent link and encompassing the semi-spherical partition thereof, the extensions having means at the ends adapted to interlock when the extension encompasses a partition.

5. A flexible shaft consisting of tubular links each having an inwardly raised, semi-spherical partition at one end thereof, each link having diametrically opposite slots at the edge of said partition, and diametrically opposite extensions from the other end of said link in a plane at right angles to the plane of the slots, said extensions engaging the slots of an adjacent link and encompassing the semi-spherical partition thereof, one of the extensions having a projection, the other of the extensions having a recess adapted to be engaged by the projection when the extensions are made to encompass a partition of an adjacent link.

6. A flexible shaft consisting of tubular links each having at one end thereof an inwardly raised, semi-spherical partition, each link having diametrically opposite slots at the edge of the partition, and diametrically opposite extensions at the other end of the link at a plane at right angles to the plane of the slots, said extensions being adapted to engage the slots of an adjacent link and encompass the partition thereof, the edge of the link at the extensions sloping symmetrically toward the extensions, the apexes of the sloping edges being in alignment with the slots and engaging the edge of the adjacent link.

7. A flexible shaft consisting of tubular links each having at one end thereof an inwardly raised, semi-spherical partition, each link having diametrically opposite slots at the edge of the partition, and diametrically opposite extensions at the other end of the link in a plane at right angles to the plane of the slots, said extensions being adapted to engage the slots of an adjacent link and encompass the partition thereof, the edge of the link at the extensions sloping symmetrically toward the extensions, the apexes of the sloping edges being in alignment with the slots and engaging the edge of the adjacent link, the center of curvature of the partition being

in the plane of the edge of the link where the partition is formed.

8. A flexible shaft consisting of tubular links each having at one end thereof an inwardly raised, semi-spherical partition forming an integral part of the link, said links having diametrically opposite slots at the edge of the partitions, and diametrically opposite extensions at the other end 10 of the link engaging the slots of an adjacent link and encompassing the partition of the adjacent link, said extensions having means locking the ends thereof, the edges of the link at the extensions sloping symmetrically toward the extensions, whereby the apexes of the slopes are in alinement with the slots, said apexes engaging the edge of the adjacent link, the center of curvature of the semi-spherical partition 15 being in the plane of the edge of the link where the partition is formed.

9. A flexible shaft consisting of tubular links each having at one end thereof an inwardly-raised, semi-spherical partition, 25 each link having diametrically opposite slots at the edge of the partition, and diametrically opposite extensions at the other end of the link in a plane at right angles

to the plane of the slots, the extensions 30 engaging the slots of an adjacent link and encompassing the partition of the said adjacent link, the edge of the link at the extensions sloping toward the extensions whereby the apexes of the slopes are in alinement with the slopes, said apexes 35 engaging the edge of the adjacent link, and a filler within each link extending from the partition of an adjacent link to the extensions of another adjacent link.

10. A flexible shaft consisting of tubular 40 links each having an inwardly raised semi-spherical partition at one end thereof, and an extension at the other end adapted to engage an adjacent link and encompass the semi-spherical partition of said adjacent 45 link, and a filler in each link extending between the semi-spherical partition and the extensions of the adjacent links respectively.

In testimony whereof I have signed my name to this specification in the presence 50 of two subscribing witnesses.

ARMAND MONARD.
